UNITED STATES PATENT OFFICE.

CLARENCE C. SHIPP, OF INDIANAPOLIS, INDIANA.

RADIATOR-CASING.

1,288,236.

Specification of Letters Patent. Patented Dec. 17, 1918.

Application filed October 30, 1916. Serial No. 128,604.

To all whom it may concern:

Be it known that I, CLARENCE C. SHIPP, a citizen of the United States, residing at Indianapolis, in the county of Marion and 5 State of Indiana, have invented certain new and useful Improvements in Radiator-Casings, of which the following is a specification.

Modern requirements dictate that heating 10 and ventilating systems installed in public school and like buildings shall conform to certain requirements which consist, generally, first, that all radiators shall be incased in casings to enable heat radiation to be controlled; second, inside air circulation must be possible when desired, and, third, that outside air can be admitted to the radiator when desired. The above requirements necessitate an apparatus whereby inside air circulation can be alternately established with that of securing air from the outside of the building, or that the two may be operated simultaneously in such relative degrees to produce the best results in the 15 condition of the air within the building, irrespective of the temperature of the air outside the building. To meet the above requirements radiator casings heretofore have had communication at the rear with air ducts leading to the outside the building and on their front sides and near the floor these casings, were provided with inlet orifices through which inside air circulation could be established. The openings through 20 the air inlet ducts leading to the outside of the building and the orifices in the front sides of the casing were controlled by separate dampers, these dampers in many cases being actuated by a single lever, while the readily discernible position of the front dampers also indicated the relative position of the rear dampers. The objections to placing the inlet orifices in front of the casings and near the floor was, first, in case 25 of school buildings, the insertion of foreign matter into the orifices by the children, and, second, the low position of the orifices permitted the inflowing air currents to carry the dust from the floor and deposit same upon the walls immediately above the radiator casings.

To overcome these previously mentioned objections it has been found expedient to remove the air intake orifices from the front

sides of the casings and place them in the 55 back sides of the casings and sufficiently above the floor, so that, with the introduction of intervening aprons between the orifices and floor, the ingoing air in gaining access to the interior of the casings is forced to enter from above and at the sides of the casings and thus carry along only such dust as may be held in suspension. Placing both orifices and their controlling dampers in the 60 back sides of the casings, however, necessitated the introduction of certain means for not only actuating said dampers but to disclose at all times their relative position.

The present invention relates to certain mechanism whereby both dampers may be 70 simultaneously actuated and their respective positions indicated; and the object of the invention consists in the provision of certain means for accomplishing the above result which is simple in construction, efficient 75 in operation, whereby the dampers may be simultaneously actuated and their positions indicated to the operator from the front of the radiator casing.

I accomplish the above object of the invention, and such others as may appear from a perusal of the specification and claims, by means of the construction illustrated in the accompanying drawings, forming a part hereof, in which—

Figure 1 is a fragmentary detail vertical sectional view through a section of a building wall, radiator casing and air inlet orifices. Fig. 2 is a fragmentary detail vertical sectional view, on the line 2—2 in Fig. 1, 90 in which the radiator is omitted. Fig. 3 is an enlarged view in side elevation of the connection between the vertical indicator rod and guide-plate. Fig. 4 is a front elevation of the construction shown in Fig. 3. Fig. 5 95 is a top or plan view of the construction shown in Fig. 4, the indicator rod being shown in section.

Referring to the drawings, 10 represents the usual and well known radiator, and 11 100 the inclosing casing which is formed of sheet metal. On the back side of the casing and near the floor the casing communicates with a wall air inlet ventilating duct 12, the latter being let into the brick-work or such 105 other material from which the wall 13 is constructed. The orifice between the casing and duct may be increased or reduced in

size by means of a damper 15 which is pivoted at 16 to the wall of duct 12. Damper 15 is actuated through the medium of a shifting rod 17 and link 18, the rod extending forward and through a slot 19 in the front wall of the radiator casing base 20 and is provided with the notches 21 adapted to engage the wall of base 20 so that the damper can be partially or entirely moved 10 to the limit of its travel. Air entering through duct 12 from the outside the building is discharged into casing 11 and after passing vertically between the heated coils of the radiator is discharged into the room 15 through the open top of said casing. Casing 11 is provided in the back wall with an orifice 25 through which inside air circulation can be established when desired. Orifice 25 is usually closed, by means of a damper 26, when air duct 12 is entirely open, but 20 the two openings may be partially open at the same time, in order to secure proper atmospheric conditions within the room by means of the adjustments secured with 25 notches 21, as heretofore described. Since the movement of damper 26 is in a direction at right angles to the general movement of rod 17, certain mechanism is interposed to not only synchronize the movements of dampers 15 and 26 but to control the distance of 30 travel of damper 26. To accomplish this result damper 26 is shifted through the medium of a vertically disposed rod 28 carrying a transverse pin 29 in which the ends of 35 said pin rest within slots 30 in yoke 31. Yoke 31 is also provided with a vertical slot 32 adapted to receive rod 28, the extended portions of yoke 31 serving to arrest lateral movement of said rod. Yoke 31 is secured 40 to damper 26, and since the metal comprising both the damper and walls of the casing is composed of thin material these parts are apt to warp and draw away from rod 28, in which case slots 30 allow for such movement 45 without causing impingement upon said rod to interfere with its normal movement. Damper 26 is moved by means of transverse pin 29 engaging the extended portions of yoke 31. See Figs. 3, 4 and 5. Operative 50 connection is provided between shifting rod 17 and vertical rod 28 through the medium of a chain 35, one end of the latter being secured at a convenient point on the rod 17 from whence the chain passes over sheave 36, 55 thence upward and over sheave 37 and thence downward and attaching to the lower end of vertical rod 28, the initial arrangement and connections of chain 35 being such that when damper 15 stands so as to entirely 60 close the opening through duct 12, damper 26, stands so as to leave orifice 25 fully open, and vice versa. Rod 28 is provided with 65 an extension member 28^a which extends up and slightly above the upper edge of casing 11, and the upper end of member 28^a car-

ries an indicator plate 38 whose purpose will be hereinafter described. Rod 28 and its member 28^a may be lengthened or shortened through the medium of a sleeve 40 and setscrew 41 in order to accommodate the rod 70 to casings of different heights. Having the above construction in mind, with the several parts occupying the positions shown in Fig. 1, when shifting rod 17 is moved in the direction indicated by the arrow to open 75 damper 15 chain 35 is carried along, and chain 35, operating over sheaves 36 and 37, moves rod 28 a sufficient distance vertically to cause damper 26 to close orifice 25, and in reversing the movement of rod 17 the movements of the associated parts are reversed. Sheaves 36 and 37 are mounted in a bracket 80 39 secured to the rear wall of casing 11.

As before stated, member 28^a carries the movable indicator plate 38 which is brought 85 into full view at the upper limit of its travel, and at the lower limit of travel said plate is hidden by means of the face-plate 45 of the stationary indicator plate 46 secured to the rear wall of casing 11 by means of the bolts 90 47. The stationary indicator plate is usually supplied with the word "shut" and is normally exposed for the reason that damper 15 normally stands to close the opening through duct 12, and damper 26 stands to 95 fully expose orifice 25, which permits unobstructed inside air circulation within the room. Movable indicator plate 38 is supplied with the word "open," and when said plate is elevated to bring the word "open" 100 into view plate 38 will so cover plate 46 to obscure the word "shut." When plate 38 is elevated to expose the word "open" it indicates that damper 15 is moved to open passageway through duct 12 and that damper 105 26 is moved to close orifice 25.

Having thus fully described my said invention, what I desire to secure by Letters Patent, is—

1. The combination, with a steam radiator 110 casing provided in its back wall with an air inlet opening leading to the outside of the building and a second opening communicating with the interior of the room, a damper for controlling the movement of air through 115 each opening, a push-rod for actuating the damper in the outlet opening for the outside air, a rod for mounting the damper for controlling the opening for the inside air, a chain for connecting the two rods together, 120 a sheave for engaging the chain and for changing the direction of travel of one rod to that of the other, and an indicator moving with said dampers, for indicating the position of each damper with its adjacent inlet 125 opening.

2. The combination, with a steam radiator casing provided in its rear wall with an air inlet opening communicating with the interior of the room, a sliding damper for 130

controlling the passage of air through said opening, a yoke carried by said damper, a movable rod, means carried by said rod for engaging said yoke to actuate said sliding 5 damper, a damper actuating rod, a flexible connection between the damper actuating rod and movable rod, and an indicator mov-

ing with said damper for indicating the position of the latter with said inlet opening.

In witness whereof I have hereunto set my 10 hand and seal at Indianapolis, Indiana, this 17th day of October, A. D. one thousand nine hundred and sixteen.

CLARENCE C. SHIPP. [L. s.].
